UNITED STATES PATENT OFFICE.

HORACE L. KENT, OF BROOKLYN, NEW YORK

CRUSHING-MILL.

1,150,864.

Specification of Letters Patent. Patented Aug. 24, 1915.

Application filed July 10, 1912. Serial No. 708,568.

To all whom it may concern:

Be it known that I, HORACE L. KENT, a citizen of the United States, and residing in Brooklyn, in the county of Kings and 5 State of New York, have invented certain new and useful Improvements in Crushing-Mills, of which the following is a full and clear specification.

This invention relates to crushing mills 10 for pulverizing various substances and has for its main general object to provide an improved construction, combination and arrangement of parts in that type of roll mills in which the rolls are swingingly suspended 15 from a rotary driving head.

One of the objects of the present invention is to provide a grinding mortar of improved construction, and a roll which co- 20 operates with said mortar without slip at any point.

Another object is to provide improved means for mounting and supporting the grinding mortar for the purpose of eliminating crystallization of the metals in cer- 25 tain parts which are peculiarly subject to crystallization, such as the roll shaft, bearing head, and parts of the frame work contiguous thereto.

A further object is to provide an im- 30 proved construction which will serve to expedite the screening action and prevent clogging thereby greatly increasing the capacity of the mill.

Another object is to provide a rotary head 35 of improved construction and improved means for flexibly mounting said rotary head from which the crushing roll is suspended, said flexible mounting contemplating the equalization of the stresses in a bearing 40 support comprising relatively adjustable parts.

Other and further objects will appear in the specification and be specifically pointed out in the appended claims, reference being 45 had to the accompanying drawings, exemplifying the invention and in which,

Figure 1 is a vertical section of a crushing mill constructed in accordance with the principles of the present invention, parts being broken away and parts shown in elevation; Fig. 2 is a top plan view of the same with the top cap removed; Fig. 3 is a top plan view with the rotary head removed, parts being broken away; Fig. 4 is a top plan view of the grinding mortar detached and with the housing and screen removed;

the drop frame and a fragment of the base ring being shown.

Referring more particularly to the drawings and to the embodiment shown therein, the main frame of the machine comprises a plurality of arched supports 1, which are mounted rigidly upon a base ring 2. Depending from the base ring 2 is an arched drop frame 3, provided with a hub 4 in 60 which is adjustably mounted a post 5, said post being held in any position to which it may be adjusted by means of a set screw 6. The upper end of the post 5 is rounded to fit the curved socket in the under face of 65 a bearing block 7, which is socketed within a depending protuberance 8 on the bottom of the mortar 9. Said mortar is provided with a grinding ring 10, which is removably seated within an annular recess in the inner 70 wall of the mortar. The inner walls of the grinding ring 10 form a continuation of the inside bottom surface of the mortar 9 and converge upwardly. A roll 11 which is 75 adapted to travel around the inner face of the ring 10 is suspended by a shaft 12 from a rotary head to be hereinafter described. In order to entirely eliminate the slip between the roll 11 and ring 10 and to make 80 the movement a purely rolling one, the roll 11 and ring 10 are respectively constructed to conform to the surfaces of a cone rolling within a cone and having a common apex at the center of the spherical journal in the 85 rotary bearing head. In this manner, true rolling contact is provided between the upper edges of the roll and ring as well as between the lower edges thereof. The lateral walls of the mortar are made with inner and outer sections spaced apart to 90 provide annular passages 13 across the upper ends of which extend the upwardly flared screen 14, which is thus adapted to 95 deliver the screened material vertically by gravity and at the same time having its inner wall forming a hopper like wall for greatly extending the screening action.

For making the parts readily accessible without entirely dismantling the machines, a housing for the apparatus just described is provided by a plurality of knock down sections 15, which are adapted to fit snugly around their lower edges in an annular recess formed for that purpose in the upper edge of the outer section of the mortar wall. An annular plate 16 has its outer periphery 100 resting upon the upper edge of the sections 110

15, being surmounted by a frusto-conical shell 17. The upper edge of the screen 14 is engaged and supported by the lugs 18. Said screen 14 is preferably made in sections to permit access to the interior of the mortar when the nuts 19 which retain the cap plate 16 in position on the bolts 20, are removed. The upper ends of the supports 1, are rigidly connected by a ring 21 provided with an angular recess 21' for the purpose of adjustably mounting the bearing ring 22, provided with sockets 23 for the radially disposed springs 24, which abut at their outer ends against the disk plates 25 on the inner ends of bolts 26, which are threaded in the upper ends of the supports 1 and serve to adjust the tension of the springs 24 and so determine the normal position of the ring 22. The inner face of the ring 22 is provided with a concave bearing surface within which the upper convex portion of a connection 27 is socketed. The lower portion of the connection 27 is threaded exteriorly to receive a gland 28, provided on its lower end with an inwardly turned flange 29 for supporting the bearing washers 30, which are usually made of suitable metals for this purpose. A bearing cone 31 is provided below with a flat annulus 32, with an upwardly deflected flange 33, which is threaded to the outer wall of the gland 28. The rotary head for operating the roll is journaled upon cone 31, and in its main essential elements comprises the pulley rim 34, which is connected by web 35 with a frusto-conical bearing hub 36. Surmounting the bearing hub 36 is a part spherical bearing member 37. As shown in Figs. 1 and 2, the rotary head is provided 40 with a receptacle for lubricant consisting of a cylindrical hub portion 38, and a pair of oppositely disposed roller sockets 39. Universally journaled upon the ball pivot 37 is a part spherical socket or bearing cap 40, from the lower edge of which projects the bearing pins or journals 41 for the rollers 42, which bear on the side walls of sockets 39, and serve to permit the desired swinging and revolving movements of the 45 roll supporting shaft 12, which is rigidly connected to the bearing socket 40. The roll 11 is rigidly mounted on the lower end of the shaft 12 and as already pointed out, is made of frusto-conical form to correspond 50 to its revolving movements and its relative disposition with respect to the rotary head. By an inspection of Fig. 1 it will be seen that the overhanging upper edge of the grinding ring 10 cooperates with the frusto-conical form of the roll 11 to prevent said roll being crowded upwardly during the pulverizing operations, thus making the pulverizing action more positive.

60 In order to provide simple and efficient means whereby the supporting ring 22 may

be caused to slide on the annular shoulder formed by the recess 21, an additional means for supporting the bearing cone 31 is provided by the plate ring 43, which is recessed as shown in Fig. 1, to seat the flat 70 base portion 32 of the bearing cone 31. The ring 43 is suspended by means of bolts 44 which permit a universal swinging movement of sufficient scope to provide for the resiliently supported vibratory movement 75 of the rotary driving head. For this purpose, the supports 1 are provided with lugs 45 with downwardly enlarged apertures, which permit the necessary swing of the bolts 44. In order to adapt the bolts 44 for 80 their rocking movements, a cupped washer 46 is interposed between the head of each bolt and the top surface of the lug upon which it rests. Threaded to the bolts 44 are nuts 47, which serve to impart a vertical ad- 85 justment to the bearing ring 43 to adjust the stresses in the rings 22 and 43 for the purpose of preventing any injurious grinding action of the ring 22 against the surface on which it slides.

As is well known, the constant jar and impact between metals of the description used in machines of this character eventually causes crystallization and consequent liability of the parts breaking under the shocks to which said machine is subjected. To avoid these difficulties, the present invention contemplates the support of the mortar from the centrally disposed post 5, such that said mortar can be rocked under proper restraint in every direction from the pivot 5. To properly restrain the movements of the mortar 9, the outer lateral wall of the mortar 9 is provided with a plurality of sockets 48, for the retention of springs 49, each bearing on their outer ends against a disk plate 50 on the inner end of an adjustment bolt 51, threaded in boss 52, on the base ring 2. In this manner crystallization of the roll shaft bearing head and contiguous parts is very largely prevented and the life of the parts greatly extended, as the hard jolts and knocks are largely absorbed by the springs 49. Coöperating with this yielding movement of the mortar 9 the yieldable mounting of the rotary head, as hereinbefore described, permits the ready and continuous adjustment of the several parts during the revolving movements of the roll 11.

I have found from my experience in operating this type of mill as formerly constructed that the ground material is not thrown through the screen with sufficient rapidity, and that in examining the mill after grinding, a large quantity of completely ground material remains in the mill. The flaring shape of screen in my improved mill greatly increases the action of the mill in discharging the ground material. I have also found from experience that the head supports, the

shaft of the roll and other smaller parts in this type of mill are crystallized from the heavy shocks and vibrations. My improved spring mountings entirely eliminate these 5 objectionable tendencies. In connection with the employment of the cone supporting ring 22, the use of the adjustable take up for the supplementary supporting ring 43, makes it possible to prevent any undesirable 10 grinding effects of the ring 22 on the annular bearing surface formed by the recess 21.

What I claim is:

1. In a crushing mill, the combination of a bearing member, means for yieldably supporting said bearing to resist its lateral displacement, a shaft having its upper end journaled on said bearing member, a receptacle within which the lower end of said shaft depends, a roll carried by said lower 20 end of the shaft to coöperate with the inner wall thereof, and means for yieldably supporting said receptacle against lateral displacement.

2. In a crushing mill, the combination of a bearing member, means for yieldably supporting said bearing to resist its lateral displacement, a shaft having its upper end journaled on said bearing member, a receptacle within which the lower end of said 30 shaft depends, a roll carried by said lower end of the shaft to coöperate with the inner wall thereof, and means for yieldably supporting said receptacle against lateral displacement, said receptacle being suitably 35 mounted to rock from side to side about a fixed point below the bottom of said receptacle.

3. In a crushing mill, the combination with a pivot, of a receptacle resting thereon 40 and capable of rocking in all directions about said pivot as a center, a shaft depending into said receptacle, a roll mounted on the depending end of said shaft and coöperating with the inner lateral wall of said 45 receptacle, means for resiliently supporting said receptacle against lateral displacement about its pivot, and means for suspending the upper end of said shaft.

4. In a crushing mill, the combination 50 with a pivot, of a receptacle resting thereon and capable of rocking in all directions about said pivot as a center, a shaft depending into said receptacle, a roll mounted on the depending end of said shaft and co- 55 operating with the inner lateral wall of said receptacle, means for resiliently supporting said receptacle against lateral displacement

about its pivot, and means for suspending the upper end of said shaft, said means including a fixed support, a bearing member 60 movably mounted thereon, and a pulley journaled on said bearing member and having said shaft suspended therefrom.

5. In a crushing mill, the combination of a fixed frame, a receptacle yieldably supported in said frame, a bearing, a shaft having its upper end journaled on said bearing, a roll carried by the lower end of said shaft and operating within said receptacle, a supporting member for said bearing, and means 70 for suspending said supporting member from said frame, said suspending means being adapted to permit said bearing to be shifted laterally during the gyratory movements of the roll within the receptacle. 75

6. In a crushing mill, the combination of a frame, bolts depending from said frame, a ring support suspended by said bolts, a bearing carried by said ring, a shaft having its upper end journaled on said bearing, a 80 roller mounted on the lower end of said shaft, and a receptacle yieldably mounted in said frame and arranged to have its inner wall coöperate with the roll on said shaft.

7. In a crushing mill, a fixed frame, a 85 bearing member carried thereby, a pulley journaled on said bearing member, a shaft depending from said pulley and having one end pivotally supported thereby, a roll mounted on the lower end of said shaft, a 90 post carried by said frame and having a rounded bearing surface, a receptacle having a centrally disposed socket with a bearing surface conforming to the upper surface of said post, and means for yieldably supporting said receptacle from said frame to prevent undue lateral movement about said post. 95

8. In a crushing mill, a resiliently mounted head, a shaft depending therefrom, a roll 100 suspended on said shaft, a receptacle into which said roll depends, and means for resiliently supporting said receptacle against lateral displacement.

9. In a crushing mill, a swingingly mounted head, a shaft depending therefrom, a roll suspended on said shaft, a receptacle within which said roll operates, and means for yieldably supporting said receptacle against lateral displacement. 105
